UNITED STATES PATENT OFFICE.

WILLIAM JOHN BURKE, OF YOUNGSTOWN, OHIO.

SAFETY DEVICE.

1,401,874.

Specification of Letters Patent. Patented Dec. 27, 1921.

Application filed December 14, 1920. Serial No. 430,710.

To all whom it may concern:

Be it known that I, WILLIAM J. BURKE, a citizen of the United States, and resident of Youngstown, in the county of Mahoning and State of Ohio, have invented a new and Improved Safety Device, of which the following is a full, clear, and exact description.

My invention relates to a safety device, and aims to provide an article of this character more particularly adapted for use in connection with rail-road rail systems.

It is a well appreciated fact that a great number of accidents have occurred, due to what is commonly known as "splitting a switch." This is to be attributed to the fact that the switch is thrown either open or closed, and these parts do not seat to their fullest extent, subsequently a train passing over the switch point, will cause the latter incident to the vibration, to be thrown into the opposite direction, thus resulting in a derailment, with often extremely serious results.

Having these defects in mind, I have constructed a safety device primarily intended for use in connection with rail switches, and by means of which any possibility of the switch being accidentally thrown upon a train passing over the same is absolutely prevented.

A second object of my invention is the provision of a device of this character which shall be entirely automatic in nature, so that the difficulty incident to the human equation is avoided.

A further object of my invention is the construction of a safety device, which will cause a complete throwing of the switch, even although the parts of the same have been carelessly left in partly closed position.

Another object of my invention is the provision of a device of the character specified, which shall be extremely simple in construction, and in which the wear which the same may receive may be compensated for, so that the device will at all times operate properly.

Further objects of my invention will appear in the annexed specification and drawings, which latter present one practical embodiment of my invention, and in which—

Figure 1 is a fragmentary plan view of a portion of a railway track and switch, showing my improved device associated with the latter.

Fig. 2 is a side view thereof.

Fig. 3 is a sectional view taken in the

direction of the arrows, and along the lines 3—3 of Fig. 1.

Fig. 4 is a view similar to Fig. 3, and taken in the direction of the arrows and 60 along the lines 4—4 of Fig. 1.

Fig. 5 is a third section corresponding to Figs. 3 and 4 and taken along the lines 5—5 in the direction of the arrows, indicated in Fig. 1.

In these views the reference numeral 10 indicates the rails, supported upon ties 11, and the reference numeral 12 the movable points of a switch, which latter may be of any desired character, but which, in the 70 embodiment illustrated, includes a pair of synchronously movable points for diverting the wheels of a vehicle to the rails 13.

Contrary to the conventional construction, a supplemental member has its ends 75 secured one to each of the points 12, by any suitable means, such as foot pieces 14, and with a view of providing an adjustment for the points 12 compensating for inequalities and wear, the pieces 14 may conveniently include a pair of oppositely screw threaded rods 15, secured together by a turn buckle 16.

Thus it will be obvious that a movement of one of the points 12 will be permitted, by virtue of the interposed member to the 85 second point 12, and also a movement bodily on the part of the member will result in a movement of the points, the distance between the latter as aforesaid, being capable of adjustment for the purposes named.

Contrary to the conventional construction, also, a pair of elements in the nature of supplemental rails 17 are conveniently positioned adjacent the outer edges of the rails 10, and are movably supported with respect 95 thereto by any suitable type of bracket, which latter conveniently includes, as has been indicated in Fig. 3, a standard 18 providing a screw threaded rod 19, properly supported and braced as at 20. These supplemental rails are pivoted at a point beyond their center so that they will normally lie as indicated in Fig. 2, with the end supporting the wedge-shaped element 23 in a plane upon the tread of the rail 10, unless depressed by the moving stock.

With a view of providing suitable means serving as a guiding element for the supplemental member connecting the switch points 12, it will be seen reference being had to Figs. 1, 2 and 4, that I may conveniently utilize plates 25, which are clamped to the

base of the rails 10 in any suitable manner, and provide guiding portions 26 through which the ends of the supplemental connecting member may extend to permit of a 5 ready transverse movement of the same.

It will now be noted, that the member connecting the points 12 of the switch preferably extend beyond the outer edges of the rails 10, as has been clearly shown in Fig. 4, 10 and this extended portion 21 of the connecting member mounts upon its outer end, an element 22, which is wedge shaped in cross section, and lies adjacent to the outer ends of the rails 17.

15 These latter carry at this point similar wedge shaped elements 23, which latter are adapted to coöperate with the former in a manner hereinafter more fully specified.

Now it will be appreciated that the tread 20 portions of the vehicle wheels will contact with the rails 17, and in some instances, this contact will be with great violence, which will cause the tendency on the part of the supplemental rails to be distorted to the 25 plane which is non-parallel to the rails 10.

To overcome this, certain of the ties 11 may conveniently carry guide elements 24, illustrated in detail in Fig. 5, the supplemental rails 17 being slidably interposed between 30 the rails 10 and the guide elements 24, whereby any lateral displacement of these rails is precluded.

It will now be appreciated that upon the 35 points of the switch being thrown by any suitable means (not shown) that the supplemental rails 17 remain in the position shown in Fig. 2, until a vehicle passing over the rails 10 contacts with said switch 17 at a point beyond their point of pivotal mounting. The free ends being now depressed by the vehicle cause the elements 23 to co- 40 operate with the similar shaped elements 22,

and thereby forcing the switch points 12 to their proper seating against the sides of the rails 10. When the train has passed the 45 switch section, the supplemental rail 17, being no longer acted upon by the weight of the vehicle, and being influenced by gravitational force of the ends opposite the opposite wedge-shaped members 10 will return to 50 their normal inclined position as shown in Fig. 2.

Thus it will be seen that I have constructed a safety device in which a connecting member moves with the switch, and 55 which connecting member has coöperating with it a relatively fixed element which will be actuated upon the passage of a vehicle, to cause a positive movement of the movable parts of the switch in the event that the 60 same are only partly thrown, and this seating of the parts will be maintained until the passage of the vehicle, at which time parts of the device will return to their normal position and leaving the switch points free for 65 subsequent manual operations.

Obviously numerous modifications of 70 structure might readily be resorted to without in the least departing from the spirit of my invention, which I claim as;

In a safety device for railway switches, the combination of switch points, foot pieces secured to the switch points, operating members lying adjacent to the rail and actuated by the rolling stock, a compression element 75 carried on one end of each of the operating members, a slide bar connecting with said foot pieces and actuated by said compression member whereby the switch points are tightly forced home, and means interposed 80 between said footpieces to adjust the same in proper spaced relation and to permit of the wear being compensated for.

WILLIAM JOHN BURKE.
